[57] **ABSTRACT**

The present invention relates to a fender having an impact-bearing surface directly or indirectly fitted with a cushion board composed of a top layer of a high softening point material or a low frictional coefficient material and a relatively hard or hard foamed layer located beneath said top layer. The cushion board according to this invention is intended for protection of the side of a ship which comes into contact with the fender and of the impact-bearing part of a fender to which this board is attached.

FENDER WITH CUSHION BOARD

DISCLOSURE OF INVENTION

The present invention is concerned with a fender equipped with a cushion board on its impact-bearing surface.

An object of this invention is to provide a fender with an impact-bearing surface which would normally come in contact with the side of a ship when in use, with a protective top layer made of a material with a high softening point or a small frictional coefficient and an intermediate elastic layer so that this impact-bearing surface would not be damaged by contact with the ship side.

There is a conventional fender with a wear-resistant sheet on its impact-bearing part, for example, U.S. Pat. No. 2,935,855, but such a sheet is torn off by impact and abrasion with the sides of the increasingly larger ship being made when they make contact with the impact-bearing part of the fender. Another conventional fender has its impact-bearing surface fitted with a wooden piece, for example, U.S. Pat. No. 3,507,123, but due to its liability to cracking and water absorption, wood is not a recommended material for this purpose.

Referring now to the accompanying drawing;

FIG. 1 is a top view of the impact surface of a fender with a cushion board in one embodiment of this invention.

FIG. 2 is an enlarged sectional view taken along line II-II of FIG. 1.

FIG. 3 is a perspective view of another embodiment of this invention.

FIGS. 4 a-c are sectional views of the cushion board.

FIG. 5 is a side view of a plurality of fenders and attached beams with a cushion thereon,

And FIG. 6 is a side view of a modified form of the invention having a cushion on a plurality of fenders and beams.

The following is a description more in detail of the embodiments of this invention referring to the attached drawing including the above-mentioned figures.

The fender 2 with the cushion board 1 riveted or glued thereto can be of any of the conventional shapes of fenders made of an elastic material, such as square, round, V-shaped or cylindrical. Embodiments in FIGS. 1 and 2 show square fenders and that in FIG. 3 is a V-shaped fender, by way of example only.

The cushion board 1 is riveted or glued to the top surface of the impact-bearing part 3 of the fender 2. As illustrated in FIGS. 1-3, it is desirable to provide a plurality of such cushion boards 1. The cushion board of FIG. 4a is composed of a low foamed layer A which constitutes the part facing the impact-bearing surface 3 of the fender and of a foamed or hardened layer B

which constitutes the part adjoining the part A and which would face a ship's side. Both layers A, B are simultaneously made of the same synthetic resin.

The cushion board 1 thus composed has its impact-bearing area B made of hard, solid material, so it is less subject to abrasion or destruction than if it were wholly fabricated of a foamed substance. In this case, ABS resin is desirable as the material.

As indicated in FIG. 4b, a sheet member B' made of a material with a high softening point or a low frictional coefficient such as polycarbonate, nylon, hardened PVC or ABS resin, polymers such as acrylnitrile, butadiene, styrene, is provided on the impact-bearing side and inside of this member B' is bonded a layer A of low foamed ABS resin or a relatively hard or hard foamed substance like hard or semi-hard rubber sponge. It is desireable that the foamed substance for the layer A in this case is an independent bubble type as in the preceding embodiment.

The cushion board 1 thus composed is directly, as shown in FIGS. 1-3, fitted to the impact-bearing part 3 of the fender, or indirectly fitted, as illustrated in FIG. 4a or FIG. 4c, with insertion of an elastic sheet C, for example of PVC, and/or an iron plate D between the impact-bearing part of the fender and the foamed layer A of the cushion board. The cushion board may be fixed as illustrated in FIGS. 1-3, or it may be fixed by appropriate means to a plurality of beams 4 laid on a plurality of fenders 2, as shown in FIG. 5 or in FIG. 6.

When a ship comes into contact with a fender thus constituted, its side slips along the impact-bearing part of the fender and thereby the fender is protected.

The hard, foamed layer covering the impact-bearing surface protects the fender, it does not break like wood and it is light weight. In the cushion board of FIG. 4b, the sheet member B' has an adequate coloring agent or fluorescent agent added during its manufacture to make the fender beautiful or more prominent in darkness.

The cushion board may become worn in long service but the worn area is limited. Therefore in a fender with a plural arrangement of cushion boards, a partial rearrangement of boards or replacement with new ones can be easily carried out.

I claim:

1. A fender for mounting on a wall or side of a dock, quay, harbor or the like for preventing ships or like vessels from harmful contact with said wall or side, the fender comprising a body portion and at least one cushion board mounted on said body portion to receive the initial impact of a ship or like, vessel against said fender, said cushion board comprising an outer layer of a material having a slidable surface and a supporting layer of a material having lightened and stiffened form.

UNITED STATES PATENT OFFICE
CERTIFICATE OF CORRECTION

Patent No. 3,680,851 Dated August 1, 1972

Inventor(s) Sadaharu Takada

It is certified that error appears in the above-identified patent and that said Letters Patent are hereby corrected as shown below:

On the cover sheet after item " 21 " and before item " 52 " insert the following:
